Samuel Heller
BY
George C. Gleason ATTORNEY

UNITED STATES PATENT OFFICE.

SAMUEL HELLER, OF NEW YORK, N. Y.

JEWELRY-CLASP.

1,314,803.

Specification of Letters Patent. Patented Sept. 2, 1919.

Application filed March 20, 1918. Serial No. 223,479.

To all whom it may concern:

Be it known that I, SAMUEL HELLER, a citizen of the United States, and resident of New York city, in the county of New York and State of New York, have invented 5 certain new and useful Improvements in Jewelry-Clasps, of which the following is a specification.

My present invention originated as an improvement in necklaces of the type in which pearls, beads or similar ornamental objects are strung on flexible cords or strings usually of silk, linen or other flexible fiber and while certain features of my invention will be 10 found useful in other relations and for other purposes, I will describe the invention in connection with a string bead necklace of the type in which it was first embodied by me.

20 Necklaces of this type require that the ends of the string be attached to the separable members of a clasp and for commercial reasons it is very important that the beads or other ornamental objects cover the 25 entire length of the string so that the portions of the string adjacent the clasp will not be left exposed to sight when the necklace is clasped upon the neck.

This is taken care of in the manufacture 30 of the necklaces by neatly tying, knotting or securing by shellac, the ends of the string to the respective members of the clasp. The pearls or other ornamental objects, usually in graduated sizes, are threaded upon the 35 string and the string being initially of greater length than required for the necklace can be neatly and conveniently tied or knotted to the clasp members after which the excess string can be cut off, making a 40 very neat job.

While there are a variety of schemes for tying, knotting, securing by shellac, etc., which are commonly practised, substantially all of them require that the pearls or other 45 beads be threaded upon a string substantially longer than the proposed necklace or other circlet so that there will be a substantial length of string left for tying of the final knot and substantially all practical 50 methods require that the surplus beyond the knot be cut off after the tying operation is completed. Hence, if a customer desires that a clasp of different workmanship, ornamentation or price be applied to a necklace 55 which he selects, the entire necklace must be restrung on a new cord or string in order to

get the surplus length required for satisfactorily retying the string to the clasp members. It is obvious that for necklaces or other circlets selling at a small price, usually by unskilled persons, the trouble and expense of changing the clasp to suit the desires of the customer will be out of proportion to the selling price of the article and hence entirely impractical as a business proposition.

To meet this necessity as to cheap necklaces, and to provide quickly detachable and easily interchangeable clasps for all kinds of necklaces and circlets, my invention contemplates the employment of what might be termed a triple clasp, that is to say, a main clasp which may be of any known or desired construction suitable for easy engagement and disengagement by the owner of the 70 necklace, and at each end of the clasp between it and the end of the string, pairs of coöperating link members at least one member of each pair being a spring or snap link adapted for snap connection with the other 75 member. Similar members of each pair of detachable links will be permanently secured to the ends of the necklace string and the other members of each pair permanently secured to the respective ends of the main 80 clasp. These pairs of detachable links will be similar for all necklaces and for all clasps so that any necklace can be easily secured to or detached from any clasp.

My invention also includes a peculiar construction of coöperating spring links suitable for the above purpose, one link member comprising a split link having hooked terminals spring pressed toward each other and the other having a pair of eye terminals 95 normally spring pressed outwardly but adapted to be compressed for insertion between the inwardly pressing hook terminals of the other member.

My invention will be more fully understood from the following detailed description in connection with the accompanying drawings, in which—

Figures 1 and 2 are side elevations partly in section of the ends of a spring bead necklace with a clasp of ordinary construction having my invention applied thereto,

Fig. 3 is a face view of a blank for a modified form of terminal link, and

Fig. 4 is a section showing the manner 110 of permanently securing the same to the string of the necklace.

In the drawings the main clasp is of a common and very well-known construction. It comprises a socket member 1, usually more or less ornamented and of more or less expensive metal; and a coöperating V-spring 2 slidably engaging the socket member and formed with a detent shoulder 3 adapted to engage a detent flange 4 on the socket member and provided with a projection 5 whereby the string may be compressed for releasing the detent. The necklace comprises the cord or string 6 having the pearls, beads or similar ornamental objects 7 strung thereon.

15 Instead of being tied directly to the clasp members 1, 2, the string is permanently secured by tying or otherwise to link members similar to each other and each formed with a perforated portion 8 for engagement 20 with the string and bifurcated link portions 9, 9 of spring material, each bifurcation having an aperture or eye 10, adapted to detachably engage with coöperating link members securing the ends of the main clasp. 25 The latter members comprise spring links 11 rigidly secured, one to the end of the socket member and the other to the end of the spring latch member of the main clasp. These link members 11 are formed with in- 30 turned ends 12, 12 spring pressed into firm engagement with each other and adapted for hook engagement with the respective eyes 10, 10 of the bifurcated members 9.

While the strings 6 may be secured to the 35 bifurcated links by any desired form of tying, indicated but not fully shown, at 13, Figs. 1 and 2, I prefer the special form of bifurcated link shown in Fig. 3 having the string secured thereto as shown in Fig. 4. 40 In Fig. 3 the link which may be formed as a stamping, has its central portion 14 concaved to form a cup with a single perforation 15 at the bottom thereof. The bifurcations 9, 9 are bent up to the position shown 45 in Fig. 4 and the string 6 is secured in the cup by passing it through the perforation 15, knotting it, cutting off the surplus string and running melted shellac into the cup on top of the knot.

50 It is obvious the detachable link members are adapted to be secured as the permanent terminal links of chain necklaces, bracelets, etc., and that by my invention all necklaces, chains, bracelets, etc., may be 55 made interchangeably and detachably securable to clasps of all the different designs and prices that may be carried in stock.

I claim:

1. An ornamental article of manufacture, 60 consisting of a fibrous cord, perforated ornamental objects strung upon said cord, terminal links having the ends of said cord secured thereto so that said ornamental objects substantially cover the entire length of 65 said string, and a main clasp comprising an

ornamental socket member and a coöperating sliding spring latch member, in combination with spring links at the respective ends of said socket and latch members formed and arranged for detachable engagement with said terminal links on said string. 70

2. An ornamental article of manufacture, 75 consisting of a fibrous cord, perforated ornamental objects strung upon said cord, terminal links having the ends of said cord secured thereto so that said ornamental objects substantially cover the entire length of said string, and a main clasp comprising an ornamental socket member and a coöperating sliding spring latch member, in combination with spring links at the respective ends of said socket and latch members formed and arranged for detachable engagement with said terminal links on said string, one link of each pair being formed with inturned ends forming hooks normally spring pressed toward each other. 80

3. An ornamental article of manufacture, 90 consisting of a fibrous cord, perforated ornamental objects strung upon said cord, terminal links having the ends of said cord secured thereto so that said ornamental objects substantially cover the entire length of said string, and a main clasp comprising 95 an ornamental socket member and a coöperating sliding spring latch member, in combination with spring links at the respective ends of said socket and latch members, formed and arranged for detachable engagement with said terminal links on said string, one link of each pair being formed with inturned ends forming hooks normally spring pressed toward each other and the other of 100 said links being formed with an opening through which said string is secured and with outwardly spring pressed bifurcations 105 formed with eyes adapted to engage with the hook members of the other link.

4. An ornamental article of manufacture, 110 consisting of a fibrous cord, perforated ornamental objects strung upon said cord, terminal links having the ends of said cord secured thereto so that said ornamental objects substantially cover the entire length of 115 said string and a main clasp comprising an ornamental socket member, and a coöperating sliding spring latch member, in combination with links at the respective ends of said socket and latch members, formed and arranged for detachable engagement with 120 said terminal links on said string, one link of each pair being formed with inturned ends forming hooks normally spring pressed toward each other, one detachable link of 125 each pair being formed with outwardly spring pressed bifurcations formed with eyes adapted to engage with the hook members of the other link.

5. An ornamental article of manufacture, 130

consisting of a fibrous cord, perforated ornamental objects strung upon said cord, terminal links having the ends of said cord secured thereto so that said ornamental objects substantially cover the entire length of said string, and a main clasp comprising an ornamental socket member and a coöperating latch member, in combination with means at the respective ends of said socket and latch members formed and arranged for detachable engagement with the respective terminal links on said cord.

6. A clasp consisting of coöperating detachable members and pairs of detachable links secured to the respective ends of said clasp members, one link of each pair being formed with inturned ends forming hooks normally spring pressed toward each other and the other of said links being formed with an opening by which a cord or chain may be secured and with adjacent, outwardly pressing bifurcations formed with eyes adapted to engage with the hook members of the other link.

25 7. An ornamental article of manufacture,

consisting of a fibrous string or cord, perforated ornamental objects strung upon said cord, terminal links having the ends of said cord secured thereto, said links being each formed with an opening through which said string is secured and with forwardly extending bifurcations of spring metal, each formed with an eye.

8. An ornamental article of manufacture, consisting of a fibrous string or cord, perforated ornamental objects strung upon said cord, terminal links having the ends of said cord secured thereto so that said ornamental objects substantially cover the entire length of said string, said links being each formed with a central cup having a central opening in which an end of said cord is knotted and secured by shellac; and integral with said cup, forwardly directed bifurcations of spring metal, each formed with an eye.

Signed at New York city in the county of New York, and State of New York this 19th day of March, A. D. 1918.

SAMUEL HELLER.

Copies of this patent may be obtained for five cents each, by addressing the "Commissioner of Patents, Washington, D. C."
